UNITED STATES PATENT OFFICE.

CHARLES H. HISER, OF SPRINGFIELD, OHIO, ASSIGNOR TO THE SPRINGFIELD METALLIC CASKET COMPANY, OF SPRINGFIELD, OHIO, A CORPORATION OF OHIO.

DEVICE FOR SEALING GRAVE-VAULTS.

SPECIFICATION forming part of Letters Patent No. 760,454, dated May 24, 1904.

Application filed April 6, 1904. Serial No. 201,854. (No model.)

To all whom it may concern:

Be it known that I, CHARLES H. HISER, a citizen of the United States, residing at Springfield, in the county of Clark and State of Ohio, 5 have invented certain new and useful Improvements in Devices for Sealing Grave-Vaults, of which the following is a specification.

My invention relates to metallic grave-vaults, and especially to means for sealing the 10 same.

Metallic grave-vaults are usually supplied with automatically-locking internal fastening devices which when once locked prevent the vault from being opened without destroying 15 the same. It is desirable in vaults of this kind to seal them hermetically against air and water, and for this purpose they are often provided with laterally-extending flanges forming a channel to receive cement to cement the 20 lid and body together. Under certain conditions, depending somewhat on the character of the cement, it becomes difficult to properly seal the casket when depending alone on the internal fastening devices. I have therefore 25 provided means for positively forcing the lid downwardly onto the body of the casket, so as to bring the cover-flange on the cement in the cement-channel and compress the same therein, causing it to flow into all the crevices and 30 completely seal the casket.

The invention consists in the constructions and combinations of parts hereinafter described, and set forth in the claims.

In the drawings, Figure 1 is an end view of 35 a grave-vault equipped with my compressing-clamps. Fig. 2 is a detail showing the compressing-clamp in engagement with the vault-cover. Figs. 3 and 4 show different positions assumed by the compressing-clamp when dis- 40 engaged from the vault-cover. Fig. 5 is a detail of a depressed seat formed in the cover-flange.

Like parts are indicated by similar reference characters throughout the several views.

45 In said drawings, *a* represents the vault-body, and *a'* the lid thereof.

a' is the flange forming the usual cement-channel about the upper edge of the body.

a' is the flange of the lid *a'*, adapted to cover the cement-channel. 50

At intervals along the sides and ends of the vault and below the flange *a'* there are attached by rivets or otherwise a series of clips *b*, having extended ears *b'*. Between the ears *b'* of each of the clips *b* there is pivoted a member *c*, which is offset at its respective ends, as shown at *c'* and *c''*. The lower portion *c'* is provided with a slot *c''*, and the upper projecting portion *c''* is preferably screw-threaded to receive a compression-screw *d*. This construction permits this hinged member to swing up over the flange, while the connecting body portion of the member is at the side of the flange and brings the screw substantially over the pivotal connection. The flange *a'* of the 65 cover is preferably provided with a slight depression *d'* opposite each of these members to receive the end of the compression-screw *d*. The hinged member is also further preferably provided with an extended guard or finger *c'*, 70 which serves as a handle for readily operating the hinged member and also as a guard to the compression-screw *d*.

In operation the channel *a'*, having been 75 filled with cement, the clamping members *c* are placed in the horizontal position (shown in Fig. 3) with the pivot in the end of the slot *c''* farthest removed from the connecting-body. By reason of the location of the pivot and the extended portion of the clamps the clamps 80 will remain in this horizontal position, (shown in Fig. 3,) the pivoted connection being in this case an eccentric one. The lid is then placed in position with the flange *a'* covering the cement-channel, after which the clamps 85 are swung to the vertical position (shown in Fig. 2) and with the screws engaging in the depressions in the top of the lid-flange. The clamping-screws are then adjusted to force the lid downwardly until the cement is pressed 90 into all the crevices, thus tightly sealing the casket. By having the clamp arranged with the slotted opening *c''* it will be seen that the clamp may be swung either above or below the pivotal point in a vertical position by caus- 95 ing the pivotal point and connection to be

moved from one end of the slot to the other, or it can be placed in horizontal position convenient for adjustment when the vault is to be sealed. Inasmuch as these lids are never 5 placed in their final position until the vault is to be sealed, owing to the internal automatic clamping devices, the normal position of the clamps when not in use will be the lower vertical position, as indicated in Fig. 4.

10 It will be seen that by the construction described a simple and at the same time a very effective and convenient device is provided.

Having thus described my invention, I claim -

15 1. In a grave-vault, the combination with a body having a cement-channel and a lid for said body having a flange adapted to cover said channel, of a clamp for said parts consisting of a member pivoted to said body portion of said vault, a screw in said pivoted member adapted to engage and bear upon the cover-flange, substantially as specified.

20 2. In combination with a grave-vault, a cover, a clamping device consisting of a piv-

oted member having a slotted pivotal connection, and a clamping member carried by said pivoted member, substantially as specified. 25

3. In combination with a grave-vault, a cover-clamp, consisting of a pivoted member, a slot in said member for the reception of the pivot, whereby the pivotal point of said member may be varied, and a screw carried by said pivoted member, substantially as and for the purpose specified. 30

4. In combination with a grave-vault, a cover-clamp consisting of a pivoted member having offset ends, a slot in one end of said member for the reception of the pivot, and a screw in the other end of said member to form a clamping device, and a projecting finger adjacent to said clamping-screw, substantially as and for the purpose specified. 40

In testimony whereof I have hereunto set my hand this 1st day of April, A. D. 1904.

CHARLES H. HISER.
